CHARLES G. HORNUNG, OF BUFFALO, NEW YORK, ASSIGNOR TO LARKIN CO. INC., OF BUFFALO, NEW YORK.

METHOD AND APPARATUS FOR SECURING CAN COVERS TO CAN BODIES.

Application filed December 9, 1926. Serial No. 153,681.

This invention relates to methods and apparatus for securing can covers or tops to can bodies, particularly applicable in connection with the type of metal cans having a double friction closure seal at the top or cover. The open end of the body of such a can has an inwardly extending flange with an outwardly opening channel formed therein, which channel receives a projecting channel formed in or depressed from the top or closure of the can, so that the channel of the top will telescope within the channel of the can body when the top is applied to the can body. The two telescoping channels are of such widths that they frictionally fit one another and provide an air tight seal between the can body and top. Such cans have been extensively used as containers for paint and many other liquids, but the postal authorities have objected to shipment through the mails of liquids in cans of this type, for the reason that the can tops are held in place by friction only, and occasionally become loosened and spill the contents of the can with resultant injury to other mail matter in the mail sack or container in which the cans are placed.

Cans have also been provided having only a single seal, with the contacting walls of such seals locked together by indentations of one wall into the other, but such cans have not been satisfactory for the shipment of liquids for the reason that it is difficult to secure contact between the cover and can body along the full length of the single seal, and the act of indenting the cover to lock the top to the can body often opens this seal sufficiently to allow leakage therethrough.

An object of this invention is to provide an improved method and apparatus for securing in closed position the tops of cans of the double seal or double friction top type, with which accidental or unintentional removal or loosening of the tops will be prevented; with which the top may, when desired, be forced open by means of a screw driver or other tool when the can is to be opened; and with which leakage at the connection between the cover and can body will be effectively prevented.

A further object of the invention is to provide an improved method and apparatus for accomplishing each and any of the above objects; with which the covers may be locked to the can bodies in a simple and dependable

manner; and which will be relatively simple and inexpensive.

Various other objects and advantages will be apparent from the following description of an embodiment of the invention, and the novel features will be particularly pointed out hereinafter in connection with the appended claims.

In the accompanying drawing:

Fig. 1 is a side elevation of one form of apparatus for locking the covers to the can bodies in accordance with this invention.

Fig. 2 is a plan of the closure head of the same;

Fig. 3 is a sectional plan of the same, with the section taken approximately along the line 3—3 of Fig. 1.

Fig. 4 is a sectional elevation of the closure head, with the section taken approximately along the line 4—4 of Fig. 3 and illustrating a can and top in operative relation thereto.

Fig. 5 is a similar sectional elevation of a part only of the construction shown in Fig. 4, and illustrating the action of a cam in indenting and locking the cover to the can body.

Fig. 6 is a sectional plan of the same, but on a larger scale, with the section taken approximately along the line 6—6 in Fig. 4, and with the cams in the same operative positions.

Fig. 7 is a view similar to Fig. 6, but with the cams in the positions occupied at the completion of one indenting operation.

Fig. 8 is a view similar to Fig. 6, but illustrating the position of a cam in the channel at the beginning of the indenting operation.

Fig. 9 is a view similar to Fig. 8, but illustrating a different type of cam which may be employed.

In the illustrated embodiment of the invention, the can body 1 (see Figs. 4 to 9) is provided at its open end or face with an inwardly extending flange 2, which has formed therein along its free edge an inwardly projecting U-shaped channel 3, that is, the inner edge of the inwardly extending flange 2 is deformed to form an annular channel groove 3 opening outwardly through the open face of the can body. The top 4 for the can is a metal plate having an annular U-shaped channel 5 formed therein at a point spaced inwardly somewhat from

its outer edge, the channel 5 of the top being of a width such that it will fit snugly and frictionally within the channel 3 of the can body when the cover is forced into 5 closed position on the can body, as shown in Figs. 4 to 8. When the top is in closed position, there will be a friction seal between contacting side walls of the two telescoping channels of the top and can body. It has 10 been found that this double friction seal is an effective liquid-tight closure, but to comply with the postal regulations, the covers must be locked in closed position by other than mere frictional contact.

15 In accordance with this invention a plurality of indenting cams 6 may be disposed in the telescoping channels and then rotated to indent into one another the contacting side walls of the channels, as shown clearly 20 in Fig. 5. These cams have one width such that they may be easily and freely shifted into and out of the channel, and each cam also has a projection 7 which may be in the nature of a more or less pointed tongue 25 or lug 7 projecting peripherally therefrom, which, when the cam is rotated about its axis within the channel, will engage with two contacting side walls at one side of the telescoping channels and provide indentations 30 8 in both of these contacting side walls, thus forming a mechanical but yieldable interlock between the cover or top and the can body.

35 The pressure exerted by the projection or lug 7, which does the indenting, upon the two contacting side walls of the channels, while causing the indentation, tends to spring laterally the side walls at both sides of the channels, with the result that in many 40 cases, the entire channel of the cover, for example, is sprung laterally. Consequently, the contacting side walls at the opposite side of the channel at the point of indentation are frequently sprung somewhat apart, thus 45 opening the frictional seal which has theretofore existed.

Occasionally the seal is also broken at the 50 points of indentation by the distortion of the side walls during the act of indentation, and therefore the seal at both sides of any 55 particular part of the channel may be broken by indenting one of the walls at one side of that part of the channel. To prevent this, each cam is provided with a tail or abut- 60 ment portion 9 disposed diametrically opposite the indenting projection 7, so that when the cam is rotated from the position shown in Fig. 6 to the position shown in Fig. 7, the tail portion will engage with the side wall of the telescopic channels, directly across the channels from the point 65 where the indentation is being made, and will act as an abutment to prevent movement of the channel side walls, directly across from the points where the indenta-

tions are being made, in the direction of indentation, thus preventing the formation by distortion of an angular kink in the channel of the cover. The contacting side walls of the channels at the points directly across 70 from the points where the indentations are being made will thus be held firmly together, and the frictional seal existing between them will not be broken by the act of indenting the directly opposite side walls of the channel. 75

If desired, the abutment or tail portion 9 may be a second indenting projecting 9^a, as shown in Fig. 9, in which case indentations will be formed in opposite side walls 80 of the telescopic channels at any particular point along the channel, but as before pointed out, there is some danger that the act of indenting may break the seal along the side walls and therefore it is preferable not 85 to form the indentations directly across from one another, as would be the case by the use of cams as shown in Fig. 9.

The indentations may be formed at both 90 sides of the channel at different points along the channel by first causing indentations at one side of the channel 9, as shown in Fig. 7, then returning the cams to the inactive positions shown in Fig. 6, causing relative movement of the cams along the channel to 95 fresh points, and then causing relative movement of the cams in the reverse direction so as to indent the opposite side walls of the channel, that is, the side walls opposite those in which the first indentations were made. 100 Thus the indentations will be formed at points spaced apart along the side walls of the channels and at either or both sides of the telescopic channels, and consequently there will, at all times, be a close frictional contact and 105 seal along the channels either at one side wall or the other.

While each cam could be provided with a suitable handle by which it may be manipulated to cause the indentations, a mechanical 110 device is preferably provided for causing a plurality of indentations simultaneously. Referring particularly to Figs. 1 to 5, the cans with the tops applied, ready for mechanical locking, can be disposed upon a 115 suitable table or support 10, which is guided for vertical movement by a depending stem 11 thereof, which reciprocates in suitable guides 12 of a standard or frame 13. The lower end of the stem 11 rests upon one end 120 of a foot lever 14, and by depressing the other end of the lever 14 with one's foot, the table and a can supported thereon may be shifted vertically toward a closure head 125 designated generally by the reference numeral 15 in Fig. 1.

The closure head 15 is supported about and in spaced relation to the table 10 in any suitable manner, such as by a bracket 16 of the standard or frame 13. The closure head 130

may include a bearing post 17, which is fixed in the bracket 16, so as to depend therefrom toward the table 10, and is provided with a reduced terminal 18 (Fig. 4) at its lower end. A plate or member 19 may be fixed to the terminal end 18 in any suitable manner, such as by a key 20, Fig. 4, and also, if desired, by a set screw 21, Fig. 3, which extends through a flange or hub 22 of the plate 19 and into contact with the terminal 18 of the post 17. An operating arm 23 is rotatably mounted upon the terminal 18 of the post 17 and abuts against the shoulder formed by the terminal 18 and the body of the post 17. A gear 24 is rotatably mounted upon the hub or boss 22 of the plate 19, between the plate 19 and the operating member 23, and may be secured to the operating arm 23 in any suitable manner, such as by screws 25, which pass through the gear and into the arm 23.

A plurality of stub shafts 26 extend through and are rotatably mounted in the plate 19 in a row around the gear 24. The end of each stub shaft 26 which extends from the plate 19 toward the arm 23 carries a pinion 27 which meshes with the gear 24, so that all of the shafts 26 will be concomitantly rotated by an oscillation or rotary movement of the arm 23 and the gear 24. The stub shafts 26 project downwardly from the plate 19, and each shaft at its lower end carries a cam 6. Thus by an arcuate movement of the handle 23, all of the pinions 27 will be rotated through a given angular extent, and likewise all of the cams 6 will be given a similar angular or rotary movement.

In the operation of a device such as illustrated, a can with the cover forced thereon is placed either upon the table or can support 10, or placed with its cover end against the closure head 15. The closure head and can are then brought together while the arm 23 is in such an angular position that all of the cams 6 will be in the relative positions shown in Fig. 6, that is, with their minimum widths extending across the channels, so that the cans may move freely into and out of the telescopic channels. This condition is shown in Fig. 4. The operator then shifts the arm 23 in one direction through a given angular extent, that is sufficient to rotate the cams in one direction through ninety degrees, that is, into the positions shown in Fig. 7, thus causing an indentation at spaced points along one of the side walls of the telescopic channels, as shown in Figs. 5 and 7. During this indentation operation, the abutment surface ends of the cams 6 will prevent distortion of the side of the telescopic channels across from the points of indentation, so that there will be no opening of the seams at such opposite points. The operator then returns the arms 23 to initial position in which the cams 6 will be in the positions shown in Fig. 6, whereupon the

can is then given an angular rotation about its own longitudinal axis, so as to place the cams 6 at different points along the channels from those previously occupied. The operator then turns the arms 23 through a similar angular extent in the opposite direction so as to rotate all of the cams in a reverse direction, as shown by dotted lines in Fig. 7, thus indenting the inner or other contacting side walls of the channels and at points spaced along the channels from the previous points of indentation. The operator then returns the arm 23 to normal, intermediate position, after which the can may be removed with its top or cover mechanically locked thereon.

It will be obvious that various changes in the details, which have been herein described and illustrated in order to explain the nature of the invention, may be made by those skilled in the art within the principle and scope of the invention as expressed in the appended claims.

I claim as my invention:—

1. The method of securing a metal can cover having a depending straight sided channel to a metal can body having an open straight sided channel at its open end and which receives the depending channel of the cover along both side walls to form a double friction seal, which comprises assembling the cover on the can body with their channels telescopically fitting one another closely and continuously along abutting side walls of the channels, and then forming telescopic protuberances in abutting side walls of both channels by indenting pressures applied to the abutting side walls from the inside of the inner channel.

2. The method of securing a metal can cover having a depending straight sided channel to a metal can body having an open straight sided channel at its open end and which receives the depending channel of the cover along both side walls to form a double friction seal, which comprises assembling the cover on the can body with their channels telescopically fitting one another closely and continuously along abutting side walls of the channels, then forming telescopic protuberances in abutting side walls of both channels by indenting pressures applied to the abutting side walls from the inside of the inner channel, and holding by a blunt abutment the abutting channel sides at the opposite side of the channel from the indentations.

3. The method of securing a metal can cover having a depending straight sided channel to a metal can body having an open straight sided channel at its open end and which receives the depending channel of the cover along both side walls to form a double friction seal, which comprises indenting a side wall of the channel of the top into the contacting side wall of the channel of the can

body, and applying a blunt abutment to the opposite side wall of the channel at the same point therein, to hold the channel against movement in the direction of indentation, whereby the indentation may be accomplished without opening of the seam at the opposite side of the channel.

4. The method of securing a metal can cover having a depending straight sided channel to a metal can body having an open channel at its open end and which receives the depending straight sided channel of the cover to form a double friction seal, which comprises applying pressure to abutting side walls of the telescopic channels in opposite directions transversely of the channels at a point within the channels, by an indenting point engaging one pair of abutting side walls and a blunt abutment engaging the side walls directly across the channels from the indenting point, to create telescopic protuberances in abutting side walls of the channels.

5. The method of securing a metal can cover having a depending straight sided channel to a metal can body having an open straight sided channel at its open end and which receives the depending channel of the cover to form a double friction seal, which comprises applying pressure to abutting side walls of the telescopic channels in opposite directions transversely of the channels at a point within the channels, by an indenting point engaging one pair of abutting side walls and a blunt abutment engaging the side walls directly across the channels from the indenting point, to create telescopic protuberances in abutting side walls of the channels, and creating such indentations alternately at opposite sides of the channel in staggered relation along the channel.

6. The method of securing a metal can cover having a depending straight sided channel to a metal can body having an open straight sided channel at its open end and which receives the depending channel of the cover to form a double friction seal, which comprises indenting into one another the contacting side walls of the channel, and holding by a blunt abutment the side wall of the channel opposite each point of indentation against movement in the direction in which the indentation is made.

7. Apparatus for securing can tops to can bodies for cans of the type in which the can body and top have telescopic channels forming a double friction seal, which comprises a support for the can body, a cam having a width smaller than the width of the channel and movable relatively to said support into the channel, means for mounting said cam for rotation about an axis transverse to the plane of the open face of the channel, so as to cause rotary movement of

the cam within the channel, said cam having a pointed portion for indenting the side wall of one channel into the contacting side wall of the other, said cam having at a point opposite the pointed portion an unpointed abutment surface engageable with the contacting side walls of the channels directly opposite the point of indentation during the indenting arc of movement, whereby distortion of the channel side walls which are engaged by the abutment surface during indenting operation will be prevented.

8. Apparatus for securing can tops to can bodies for cans of the type in which the can body and top have telescopic channels forming a double friction seal, which comprises a support for the can body, a cam having one width permitting its free movement through the open face of the telescopic channels, means by which the cam may be given rotary motion while within the channels, said cam having a tongue portion for indenting the contacting walls of the channels with which it engages during such rotary motion and also having an unpointed abutment cam surface movable into contact with the side of the channels across from the point of indentation, for holding said channel walls of said last mentioned side against movement in the direction of indentation during such rotary motion.

9. Apparatus for securing can tops to can bodies for cans of the type in which the can body and top have telescopic channels forming a double friction seal, which comprises a support for the can body, a closure member, a plurality of stub shafts rotatably supported by said member and projecting therefrom toward said support, a cam carried upon the projecting end of each shaft and having one width permitting its movement into and out of the telescopic channels when in one angular position and having a pointed projection engageable with one pair of contacting side walls during angular movement from said position through approximately ninety degrees, so as to indent such contacting side walls at the point of engagement, and means carried by said member for rotating all of said shafts to cause indentations of the channel side walls at a plurality of points spaced along the channel, each cam also having an unpointed abutment surface opposite the pointed portion which engages with the channel side walls across from the points of indentation during the indenting operation for preventing movement of the side walls of the channel, at the points opposite the indentations, in the direction of indentation, and thus preventing opening of the seams by distortion of the channels of the top and can body during the indenting operation.

CHARLES G. HORNUNG.
